Term of patent 14 years

U.S. Cl. D87—5
Int. Cl. D3—02

FIG. 1

FIG. 2

FIG. 3

FIG. 4

FIG. 5

FIG. 6

FIG. 1 is a front elevational view of the information chart showing my new design in a closed position;

FIG. 2 is a front elevational view of the chart shown in FIG. 1 in an open position, the back thereof being substantially similar;

FIG. 3 is a top plan view of the chart shown in FIG. 1 in a partially folded position;

FIG. 4 is a perspective view of another embodiment wherein the chart is bound together in book form rather than in tri-fold form;

FIG. 5 is a side perspective view of the chart shown in FIG. 4; and

FIG. 6 is a top plan view of the chart shown in FIG. 4.

The stipple bar shown adjacent the window openings of the charts represents a color contrast without indicating any particular color.

I claim:

The ornamental design for an information chart, substantially as shown and described.
